Patented Apr. 12, 1966

204,383

TIP FOR AN ELECTRIC SOLDERING GUN

Edward T. Rodgers, 289 N. Roanoke Ave.,
Youngstown, Ohio

Filed July 30, 1965, Ser. No. 86,369

Term of patent 14 years

(Cl. D26—1)

FIGURE 1 is a top plan view of a tip for an electric soldering gun, showing my new design;

FIGURE 2 is a side elevation thereof;

FIGURE 3 is a front view thereof.

The bottom and the opposite side are substantial duplicates of the side shown.

I claim:

The ornamental design for a tip for an electric soldering gun, as shown and described.
